LEAKPROOF INKWELL

William J. Bargen, Waukegan, Ill.

Application December 9, 1940, Serial No. 369,347

20 Claims. (Cl. 120—68)

This invention relates to an inkwell. More particularly, the invention is concerned with a novel type of inkwell for use in connection with a desk top. It has now become a widespread custom in institutions of learning and in other places where desks are used, to use desks of the movable pedestal type which can readily be arranged in any desired pattern in a room and which can be stacked up out of the way when not in use. As these desks are not stationary in the sense of being fixed to the floor, they are subject to being tilted either laterally, forwardly or rearwardly. When inkwells of the ordinary type, as heretofore used are provided, the ink will sometimes spill out of the well. Often, these desks are provided with lifting tops, into which it is sometimes desirable to have an inkwell fastened.

It is a primary object, therefore, of this invention to provide a vacuum type inkwell, which is equally adaptable to either fixed or movable type desks, and in which there will be no danger, at any time, of any ink spilling from the well.

It is a further object of this invention to provide a vacuum type inkwell, so constructed and arranged, that there will always be provided an ink reservoir portion and fount portion for a pen, automatically fed by the reservoir portion.

A still further object of this invention is to provide a slidable closure in a fountain inkwell which is so constructed and arranged that tilting of the inkwell longitudinally thereof in either direction will automatically shift the closure to a closed position so as to thereby prevent spilling of the ink.

A further object of this invention is to provide an inkwell of this type having a slidable closure which will automatically shift to a closed position upon raising of the reservoir end of the inkwell so as to cut off entrance of air and thereby prevent spilling of the ink.

A further object of this invention is to provide an inkwell of the fountain type which includes an auxiliary closed chamber at one end of the main reservoir in which ink is adapted to flow in the event the fount end of the inkwell is raised, so that in the event the main reservoir is completely filled with ink, the ink in the fount may flow back to the main reservoir and enough ink from the main reservoir will flow into the auxiliary chamber to prevent overflow of the ink.

Embodying the aims aforesaid and others which may hereinafter appear, the invention consists of the novel construction, combination and arrangement of parts as will be more spe-

cifically referred to and illustrated in the accompanying drawings, wherein is shown an embodiment of the invention, but it is to be understood that changes, variations and modifications may be resorted to which fall within the scope of the invention as claimed.

In the drawings:

Figure 1 is a top plan view broken away of an inkwell in accordance with this invention,

10 Figure 2 is a section on line 2—2 Figure 1,

Figure 3 is a section on line 3—3 Figure 2,

Figure 4 is a section on line 4—4 Figure 2,

Figure 5 is a section on line 5—5 Figure 2,

Figure 6 is a section on line 6—6 Figure 2,

15 and

Figure 7 is a fragmentary view in inverted plan of the top section on the body part of the inkwell.

Figure 8 is a sectional view taken on the line 20 8—8 of Figure 3.

Figure 9 is a sectional view similar to Figure 8, but showing the device with one end raised.

Figure 10 is a sectional view similar to Figure 8, but showing the device in a reverse tilted position to that shown in Figure 9.

The inkwell, in accordance with this invention, includes a one-piece composite body part having an inlet and a closure slide shiftably mounted within the body part. The latter is formed of upper, intermediate and lower sections disposed in superposed relation and suitably secured together by heating or otherwise. The sections of the body part may be constructed of glass either transparent or translucent and suitably colored if desired, or such sections may be formed of cellulosic composition material, such as Bakelite, which may also be suitably colored. The top section of the body part may be colored in the manner to conceal the slide.

40 The body part of the inkwell is generally indicated at A and it is formed of an upper or outer section 1, an intermediate section 2 and an inner or lower section 3. The sections are disposed in superimposed relation.

45 The section 1 includes a slab-like upper portion 4 of rectangular contour, which is of greater width and length than any one of the other of the sections. The section 1 also includes an endless flange 5 of oval contour. The flange 5 is integral with the lower face 6 of portion 4 and its ends and sides are inset with respect to the ends and sides of the portion 4. The section 1 has formed integral with the lower face of portion 4 a transversely extending rib 7, which is arranged between and is integral with the flange

5. The rib 7 is arranged in proximity to one end of the flange 5. The portion 4 at one side of its transverse median and its end 8 is formed with a flared inlet opening 9 for the passage of a pen into the well. The opening 9 is intersected by the longitudinal median of the portion 4. The latter between the opening 9 and its side edge 10 is formed lengthwise thereof with a rectangular slot 11 and with the transverse median of said slot aligning with the axis of the inlet 9.

The section 2 includes an oval-shaped slab-like upper portion 12 of an outline corresponding in contour to the flange 5. The portion 12 is secured to the bottom edge and is flush with the outer side edge of flange 5. The portion 12 is formed with a segmental-shaped opening 13 at one end and is also provided with a pair of spaced recesses 14 and 15 in its upper face to form tracks 16 at its sides and also a support 17 between and aligned with the tracks. The purpose of the tracks and the support 17 will be referred to. The support 17 is formed with an opening 18 which aligns with the opening 9. Integral with the lower face of and of less length than the length of portion 12 is a depending oval-shaped wall forming member 19, which is integral at its end 20 with the end 21 of portion 12 and at its other end 22 is integral with the portion 12 at a point removed from the other end of the latter. Integral with the lower face of portion 10, depending within the member 19 and spaced from the end 22 of the latter is a partition 23 having its lower end flush with the lower end of member 19. The partition 23 coacts with the end 20 of the member 19 and also with a part of the section 1 and section 3 to provide an ink reservoir 24. The partition 23 correlates with the end 22 of the member 19 to form a passage 25 for the pen, not shown. The opening 18 communicates with the upper end of the passage 25. The member 19 and partition 23 are cut out at their lower portions, as indicated at 26, Figure 5, to provide ports for establishing communication between the reservoir 24 and a container or well-forming member to be referred to. The portion 12 abuts and is secured to the rib 7 (Figure 2).

The section 3 includes an oval-shaped slab 27, which abuts against and is secured to the bottom edge of the member 19. A part of the slab 27 forms the bottom wall of the reservoir 24. The slab 27 is provided with a tapered opening 26 and it also has integral therewith a depending tapered open top container or well-forming member 29, having its inner face forming a depending continuation of the wall of the opening 29. The member 29 aligns with the passage 25.

The section 1 coacts with the portion 12 of the section 2 to form a horizontally disposed chamber 30, in which is slidably mounted a slide 31 for the purpose of closing the openings 9 and 18, when the inkwell is shifted from normal position, that is to say when the desk is moved. The slide 31 is arranged in the chamber 30 upon the tracks 16 and the support 17 and it is provided with an opening 32 for registering with the openings 9 and 18 to permit of the passage of the pen into the container or well 29 for receiving the ink supplied to such container or well from the reservoir 24. The slide 31 has an upstanding finger piece 33, which extends through the slot 11 and is employed for manually shifting the slide to bring the opening 32 into registry with the openings 9 and 18. The end walls of 75

the slot 11 limit the shifting of the slide 31 in opposite directions.

When the slide acts to prevent a discharge of ink from the inkwell, it moves by gravitation due to the inclination of the desk when the latter is tilted and this gravitation movable action is had on the tilting of the desk laterally. When the desk is tilted a non-apertured part of the slide 31 is positioned between the openings 9 and 18 and under such conditions acts to prevent a discharge of the ink.

The insetting of the flange 5, with respect to the edges of the portion 4 provides the latter with an overhang, as indicated at 34, and this overhang is provided for the purpose of suspending the inkwell in an opening in the desk top, which is provided for receiving the major portion of the inkwell. That portion of the inkwell 1 arranged in the desk top, is adapted to be secured to the latter by any suitable means.

In the use and operation of this improved inkwell, the device is adapted to be mounted in the top of the desk and where the desk is provided with a hinged top, the device is preferably positioned parallel with one side edge of the top and with the reservoir 24 toward the desk front. When the top is in a normal position, the well will be inclined forwardly to a slight degree due to the inclination of the desk top, but this forward inclination will not materially affect the quantity of ink which is positioned in the dipping well or fount. In Figure 8 the well is shown in a horizontal position and it will be noted that in this position, the ink in the reservoir 24 will be at a higher level than the level of the ink in the dipping well 29 and the chamber 25. The auxiliary reservoir 13 at this time will be empty. In the event the forward or free edge of the top is raised, the inkwell will assume substantially the position shown in Figure 9. In this position, the slide or valve member 31 will gravitationally move downwardly so as to position the opening 32 therein out of registry with the openings 9 and 18. The ink will flow into the auxiliary reservoir 13 and will drain at least partly out of the dipping well 29 into the main reservoir 24.

In the event the inkwell is turned to a vertical position with the reservoir 24 lowermost, the ink from the well 29 will substantially flow into the reservoir 24, the auxiliary reservoir 13 providing sufficient space to receive the ink from the well 29 so that in a vertical position, the ink will be entirely contained in the reservoir 24. This obtains in the event the reservoir 24 is initially completely filled.

In Figure 10, there is disclosed a second or reversed position of the inkwell wherein the reservoir 20 is raised above the well 29. In this position the valve or slide 31 will move forwardly to the position shown so as to close the passage between the openings 9 and 18. The ink in the well or fount 29 will remain therein and some ink from the reservoir 24 will flow into the chamber 25. However, due to the fact that the slide 31 has closed the openings 9 and 18, the air above the level of the liquid in the chamber 25 will be trapped and in this manner, the ink in the chamber 25 will not be permitted to leak out of the passages 9 and 18. It will be noted in Figure 10 that the ink in the reservoir 24 is at a higher level than the ink in the chamber 25. This is due partly to the fact that the ink closes the openings 26 between the reservoir 24 and the chamber 25 so that a partial vacuum is formed in the auxiliary reservoir 13 and the rear upper

portion of the reservoir 24. It has been found from actual experience that the inkwell herein shown will not leak ink in the event the reservoir 24 is raised to a vertical position above the chamber 25.

In Figures 8, 9 and 10 the left side of the inkwell here shown is designated the front which will be disposed away from the desk occupant.

What I claim is:

1. An inkwell comprising a body adapted to be secured to a support and formed with an ink reservoir, an ink receiver below one end of the reservoir, ports leading from the bottom of the reservoir to the top of the receiver, normally open passage-forming means to permit of the insertion of a pen in said receiver and a slide chamber intersecting said means and disposed above said reservoir, and a normally stationary slide in said chamber formed with an opening normally registering with said means and capable of moving gravitationally to an extent, when the support is moved to provide for closing said means to thereby prevent discharge of ink.

2. An inkwell comprising a body adapted to be secured to a support and formed with an ink reservoir, an ink receiver below one end of the reservoir, ports leading from the bottom of the reservoir to the top of the receiver, normally open passage forming means to permit of the insertion of a pen in said receiver and a slide chamber intersecting said means and disposed above said reservoir, and a normally stationary slide in said chamber formed with an opening normally registering with said means and capable of moving gravitationally to an extent, when the support is moved to provide for closing said means to thereby prevent discharge of ink, said body including a partition forming an end wall of the reservoir and a part of one of the side walls of said means.

3. An inkwell comprising a body adapted to be secured to a support and formed with an ink reservoir, an ink receiver below one end of the reservoir, ports leading from the bottom of the reservoir to the top of the receiver, normally open passage forming means to permit of the insertion of a pen in said receiver and a slide chamber intersecting said means and disposed above said reservoir, a normally stationary slide in said chamber formed with an opening normally registering with said means and capable of moving gravitationally to an extent, when the support is moved to provide for closing said means to thereby prevent discharge of ink, said body being formed at the top with a slot opening in said chamber, and means for manually shifting said slide connected to the latter and extending outwardly through said slot.

4. An inkwell comprising a one-piece composite body adapted to be secured to a support and formed of an outer section, an intermediate section and a lower section, said outer section being provided with an inlet, said intermediate section having a part depending from said outer section and forming in connection with the said outer and inner section an ink reservoir, said intermediate section being provided with a passage for a pen and an opening communicating with the said passage registering in spaced relation with said inlet, said outer and intermediate sections having correlating means providing a slide chamber therebetween, said inner section being formed with a depending ink receiver communicating at its upper end with said passage and arranged below one end of the reservoir, said

intermediate section being formed with ports for establishing communication between said reservoir and said receiver, a gravitationally movable slide arranged in said chamber and having means for normally establishing communication between said inlet and receiver and automatically moving by gravity, when the support is moved for shutting off communication between the inlet and the receiver.

5. An inkwell comprising a body part adapted to be fixed within a support and being formed with an overhang positioned on the upper face of the support, said body part including an ink reservoir, an ink receiver below and adjacent one end of the reservoir, ports leading from the reservoir and opening into the receiver, a normally open passage forming means to permit of the insertion of a pen into the receiver and a slide chamber intersecting said means and disposed above the reservoir, and a normally stationary slide in said chamber formed with an opening normally registering with said means and capable of moving gravitationally to an extent, when the support is moved for closing said means to thereby prevent discharge of ink.

6. An inkwell comprising a body part adapted to be fixed within a support and including an ink reservoir, an ink receiver below and adjacent one end of the reservoir, ports leading from the reservoir and opening into the receiver, a normally open passage forming means to permit of the insertion of a pen into the receiver and a slide chamber intersecting said means and disposed above the reservoir, and a normally stationary slide in said chamber formed intermediate its ends with an opening normally registering with said means and capable of moving gravitationally to an extent, when the support is moved for closing said means to thereby prevent discharge of ink.

7. An inkwell comprising a body part adapted to be fixed within a support and being formed with an overhang positioned on the upper face of the support, said body part including an ink reservoir, an ink receiver below and adjacent one end of the reservoir, ports leading from the reservoir and opening into the receiver, a normally open passage forming means to permit of the insertion of a pen into the receiver and a slide chamber intersecting said means and disposed above the reservoir, a normally stationary slide in said chamber formed intermediate its ends with an opening normally registering with said means and capable of moving gravitationally to an extent, when the support is moved for closing said means to thereby prevent discharge of ink, and horizontally shiftable means extending from said body part for restoring the slide to normal position.

8. An inkwell comprising a body part adapted to be fixed within a support and including an ink reservoir, an ink receiver below and adjacent one end of the reservoir, ports leading from the reservoir and opening into the receiver, a normally open passage forming means to permit of the insertion of a pen into the receiver and a slide chamber intersecting said means and disposed above the reservoir, a normally stationary slide in said chamber formed intermediate its ends with an opening normally registering with said means and capable of moving gravitationally to an extent, when the support is moved for closing said means to thereby prevent discharge of ink, and horizontally shiftable means extending from

said body part for restoring the slide to normal position.

9. An inkwell comprising a body adapted to be secured to a support and formed with an ink receiver, an ink reservoir arranged above and to one side for the receiver, ports for conducting ink from the reservoir to said receiver, a pen passage leading to the receiver and means preventing splashing or throwing of the ink when the support is moved or dropped suddenly while controlling the level of the ink in said receiver, and an apertured automatically shiftable slide mounted in said body intersecting said passage for closing the latter to prevent discharge of ink from said body when the support is moved.

10. An inkwell comprising a body adapted to be secured to a support and formed with an ink receiver, an ink reservoir arranged above and to one side for the receiver, ports for conducting ink from the reservoir to said receiver, a pen passage leading to the receiver and means preventing splashing or throwing of the ink when the support is moved or dropped suddenly while controlling the level of the ink in said receiver, an apertured automatically shiftable slide mounted in said body intersecting said passage for closing the latter to prevent discharge of ink from said body when the support is moved, means for limiting the extent of the shifting of the slide in opposite directions, and means for positioning the slide to open the passage.

11. As a new article of manufacture, a fountain inkwell comprising a closed reservoir body, a fount extending below said body adjacent one end thereof, said body having an opening in a wall thereof whereby the liquid in said body may flow into said fount, a chamber extending upwardly from said fount, an apertured closure for said chamber, and means slidably mounting said closure for movement relative to said chamber, said closure gravitatingly shifting to a chamber closing position upon raising of either end of said body to thereby seal said chamber against entrance of air or outlet of ink.

12. As a new article of manufacture, a fountain inkwell comprising a closed reservoir body, a fount extending below said body adjacent one end thereof, said body having an opening in a wall thereof whereby the liquid in said body may flow into said fount, a chamber extending upwardly from said fount, an apertured closure for said chamber, means slidably mounting said closure for movement relative to said chamber, said closure gravitatingly shifting to a chamber closing position upon raising of either end of said body to thereby seal said chamber against entrance of air or outlet of ink, and an auxiliary chamber communicating with and extending upwardly from said body and adapted to receive ink therein upon raising of the fount end of said body whereby all of the ink from said fount may flow into said reservoir when the inkwell is tilted to position the fount in a horizontal plane above said body.

13. As an article of manufacture, an inkwell having a well forming chamber, an ink storing reservoir disposed above one side of and opening into said chamber, an apertured main closure or top common to said chamber and said reservoir, and an apertured slidable auxiliary closure shiftable to open or close the aperture in said closure or top, for providing access to said well forming chamber, said closure being loosely connected to said top.

14. As an article of manufacture, an inkwell

comprising a body including side and end walls, a bottom wall and a top wall, a partition extending between said side walls dividing said body into a main reservoir and a dipping chamber, a dipping well carried by and extending downwardly from said bottom wall and communicating with said dipping chamber, said partition having a lower passage communicating the lower portion of said reservoir with said dipping chamber, said top wall having an opening communicating with said dipping chamber, and an apertured closure movably engaging said top wall, tilting of said body in opposite directions effecting gravitational movement of said closure to a closed position.

15. As an article of manufacture, an inkwell comprising a body including side and end walls, a bottom wall and a top wall, a partition extending between said side walls dividing said body into a main reservoir and a dipping chamber, a dipping well carried by and extending downwardly from said bottom wall and communicating with said dipping chamber, said partition having a lower passage communicating the lower portion of said reservoir with said dipping chamber, said top wall having an opening communicating with said dipping chamber, an apertured closure movably engaging said top wall, tilting of said body in opposite directions effecting gravitational movement of said closure to a closed position, said top wall at one end thereof terminating inwardly of an adjacent end wall, an upper wall spaced from said top wall, a flange carried by said upper wall fixed to said top wall and said adjacent end wall, and a transverse partition carried by said upper wall and fixed to said one end of said top wall and forming with said flange an auxiliary pocket disposed above communicating with said reservoir at the end thereof opposite from said first partition.

16. As an article of manufacture, an inkwell having an ink receiver, an ink storage reservoir arranged above and opening at one end into said receiver, a pen passage disposed over, opening at one end into said receiver and arranged in juxtaposition to the said end of the reservoir and a top common to said reservoir and passage, said top being disposed in lateral relation with respect to said passage and formed with means to permit of access to said passage, and apertured means disposed in slidable relation with respect to said top and correlated with the said other means for controlling access to said passage.

17. As an article of manufacture, an inkwell having an ink receiver, an ink storage reservoir arranged above and opening at one end into said receiver, a pen passage disposed over, opening at one end into said receiver and arranged in juxtaposition to the said end of the reservoir and a top common to said reservoir and passage, said top being disposed in lateral relation with respect to said passage and formed with means to permit of access to said passage, apertured means disposed in slidable relation with respect to said top and correlated with the said other means for controlling access to said passage, said apertured means being loosely confined in said top, and said top and apertured means having coacting means intermediate their ends for limiting the extent of the sliding movement of the said apertured means in opposite directions.

18. As an article of manufacture, an inkwell having an ink receiver, an ink storage reservoir arranged above and opening at one end into said

receiver, a pen passage disposed over, opening at one end into said receiver and arranged in juxtaposition to the said end of the reservoir and a top common to said reservoir and passage, said top being disposed in lateral relation with respect to said passage and formed with means to permit of access to said passage, and apertured means disposed in slidable relation with respect to said top and correlated with the said other means for controlling access to said passage, the said receiver being disposed in depending relation with respect to said reservoir and passage.

19. As an article of manufacture, an inkwell having an ink receiver, an ink storage reservoir opening into said receiver and a top common to said reservoir and receiver and disposed in lateral relation with respect to the receiver, said top being formed with a chamber and with means

5 opening into the chamber for access to the receiver, and an apertured means slidably mounted in said chamber and correlated with the said other means for controlling access to said receiver.

10 20. As an article of manufacture, an inkwell having an ink receiver, an ink storage reservoir to said reservoir and receiver and disposed in lateral relation with respect to the receiver, said top being formed with a chamber and with means opening into the chamber for access to the receiver, and an apertured means slidably mounted in said chamber and correlated with the said other means for controlling access to said receiver, said receiver disposed in depending relation with respect to one end of the bottom of said reservoir.

15 WILLIAM J. BARGEN.
